UNITED STATES PATENT OFFICE.

ANTON J. HAUG, OF NASHUA, NEW HAMPSHIRE, ASSIGNOR TO IMPROVED PAPER MACHINERY COMPANY, OF NASHUA, NEW HAMPSHIRE, A CORPORATION OF MAINE.

PULP-HANDLING MACHINE.

1,183,298.

Specification of Letters Patent. Patented May 16, 1916.

Application filed April 24, 1915. Serial No. 23,782.

To all whom it may concern:

Be it known that I, ANTON J. HAUG, a citizen of the United States, and a resident of Nashua, county of Hillsboro, State of New Hampshire, United States of America, have invented an Improvement in Pulp-Handling Machines, of which the following description, in connection with the accompanying drawings, is a specification, like characters on the drawings representing like parts.

This invention relates to machines for screening or sorting various materials, and more particularly pulp handling machines, such as screening machines and knotters used in the manufacture of paper, for example, to remove the knots, slivers, and the like from the pulp.

The objects and features of the invention will best be understood from the following description, taken in connection with the accompanying drawings, of a machine embodying one form of said invention selected for the purpose of illustration, it being understood that the invention in its true scope is definitely set forth by the claims.

In the drawings: Figure 1 is a lateral perspective view of a pulp screening machine or knitter embodying one form of the invention, one of the exterior casing sections or plates being removed to show the screening and drying drum; Fig. 2 is a longitudinal sectional elevation of the pulp screening machine or knitter shown in Fig. 1; Fig. 3 is a transverse sectional elevation on line 3—3 of Fig. 2, looking from the left of the latter figure; Fig. 4 is a transverse sectional elevation on line 4—4 of Fig. 2, looking from the left of the latter figure; Fig. 5 is a longitudinal sectional elevation of a separating screen or drum, showing more particularly the radial frames and plates and means for securing the screening plates in place; Fig. 6 is a cross-section of a radial frame and plate carried thereby; Fig. 7 is a longitudinal sectional elevation of a portion of a second, or drying, drum or cylinder; Fig. 8 is a cross-section of one of the longitudinal ribs for supporting the screening plates of the drying drum; Fig. 9 is a perspective view, more particularly of the feed-trough, by which the material is fed into the separating drum, and of the chute, by which the knots, etc., retained in said drum, are fed into the drying drum; Figs. 10 and 11 are transverse

sections on lines 10—10 and 11—11 of Fig. 9; Figs. 12 and 13 are details of the screening plate securing or clamping means; Fig. 14 is a detail of a clamping means for the screening plates of the drying drum; Fig. 15 is an end view of the spider that carries the radial plates and other associate parts; Fig. 16 is a detail of a spacing member or ring for the radial plates, seen from the right in Fig. 2.

The invention will herein be described and illustrated in its application to a pulp screening machine or knitter, but it is not to be considered as limited to such application, since as to various features it is equally applicable to a great variety of analogous machines or apparatus, as for example apparatus or machines for screening sewage, sorting or separating crushed ores and many others.

Referring more particularly to Figs. 1 and 2, the frame of the machine in the embodiment illustrated comprises two circular end castings 2, 3, joined at their peripheries by longitudinal, curved plates 4, 4, which form the lateral walls of the outer casing of the machine, the whole being of substantially cylindrical shape. The two upper plates 4, 4, may be made removable, one being shown removed in Fig. 1. Each end casting is provided with a central, circular opening 6, 6 and with feet 8, 8, which may be bolted to the floor or other supporting surface upon which the machine is sustained. For convenience of construction and assembling each end casting will preferably be formed in two semi-circular sections provided with outwardly extending flanges 10 along their straight edges, whereby the two sections of each end casting may be secured together by bolts extending through said flanges as shown in Fig. 1, or in any other suitable manner. The lower section of the end casting 2, Figs. 1 and 2, is provided with a relatively deep, semi-circular flange 11, extending outwardly from the edge of the semi-circular central opening of said section. This flange 11 embraces and supports the feed-trough 12, which at that part is of semi-circular contour to fit said flange 11 through which it extends into the interior of the machine. Exterior to the machine, the trough 12 is provided with an opening 14 for the reception of the pulp material to be screened. The trough 12 is provided at a

point adjacent its inner end with an opening 15, whence the material, passing through the trough, escapes into the screening drum or cylinder 16, and in accordance with the 5 present invention, this opening is preferably provided in the side of the trough, as shown in Fig. 9, and extends substantially the whole length of the drum, the material being delivered therefrom in the form of a sheet, extending substantially throughout the length of the drum. This arrangement is advantageous in that amongst other things the material in passing from the trough into the screening drum 16, facilitates and may 10 contribute to the rotation of the latter.

In the embodiment of the invention chosen for illustrative purposes, the screening drum may be constructed as follows: To the shaft 18, mounted in suitable fixed 20 bearings 20, 22 and extending longitudinally of the machine, is secured in any suitable manner a hub 24 provided with four arms 26 extending outwardly from the hub at right angles to each other. To these 25 arms is secured in any suitable manner, as by bolts 28, a spider 30. Herein the perimeter of said spider is polygonal, and said spider is provided with a circular central opening 32 and a plurality of openings 34 30 adjacent its outer margin, Fig. 15. In the embodiment of the invention illustrated, this spider serves to sustain the end plates 36, 37 and peripheral screen plates 38, which form the walls of the screening 35 drum, as also the radial plates 40, which divide the interior of the screening drum into pockets for a purpose hereinafter more fully described. It also supports the screening plate sustaining ribs of the hereinafter 40 described drying drum, at one end of the latter.

In accordance with the present invention the end plates and peripheral screening plates of the screening drum are preferably 45 made removable, and the invention contemplates novel means for removably securing said plates in position. To this end, Figs. 2 and 5, the spider 30 is provided with a flange 42 extending around the outer perimeter of said spider, said flange being inclined outwardly to the plane of the spider, preferably at an angle of substantially 45°, and provided with a plurality of bolt holes 43. Frames 45 for sustaining the radial 50 plates extend radially inward from the apices of the angles of the polygonal perimeter of the spider to a point just beyond the inner edge of the marginal openings in the latter, and are secured to the inner surface of said spider by bolts 44 and 28, Fig. 5, extending through bosses 46 and 48 provided on said spider, and through eyes 47, 49 on said frames, each frame, when in place, thus projecting at right angles from the inner surface of said spider. Each

frame 45, Fig. 6, is provided adjacent its outer edge, and upon each face, with supporting ledges 54, 56, which are preferably inclined downwardly, away from said edge, which latter carries a plurality of perforated ears 50.

At their free ends the radial plate supporting frames 45 are secured in any suitable manner, as by bolts 58 and 59, to a spacing member or disk 60, having a circular, central opening 62, Fig. 2, and marginal openings 64. Adjacent its outer edge, said spacing member or disk is provided with an outwardly inclined flange 66, similar to the flange 42 provided on the spider 30 above described. The peripheral screening plates 38 are laid with their longitudinal edges resting, one on the flange 56 of a frame 45 and the other on the flange 54 of the next following frame 45, the end edges 80 of said peripheral screening plates resting, one on an inwardly projecting flange 68 of the spider 30 and the other on an inwardly projecting flange 70 provided on the spacing member 60. Clamping or securing bolts 72, 90 provided with nuts 74 extend through the holes in the flange 42 and carry clamping or securing members 76 having beveled edges 78, Fig. 5. Similarly bolts 80 provided with nuts 81 extend through the holes on the 95 ears 50 on the outer edges of the frames 45 and carry upon either side of said ears 50 clamping or securing members 82 having beveled edges 84, similar to the clamping members 76. The flange 66 of the spacing 100 member 60 is provided with holes to receive bolts 86 carrying nuts 88 and clamping members 90 with beveled edges 92 similar to the clamping members 76 and 82 above described. It will be seen that by tightening 105 nuts 74 on bolts 72, nuts 81 on bolts 80, and nuts 88 on bolts 86 the peripheral screening plates 38 will be firmly and removably clamped or secured in place around the screening drum.

The marginal openings 34, provided in the spider 30, and the marginal openings 64 provided in the spacing member or plate 60 are covered by the end plates 36 and 37, respectively, which are removably clamped 110 or secured in place along their outer edges by clamping members 98 and 100, respectively, carried by bolts 72 and 86. Herein said end plates are shown as unperforated, but they may be perforated to constitute 115 end screen plates, if desired. The openings 101 in the frames 45 are covered by the radial plates 40, which are secured to said frames in any suitable manner, as by bolts 103. The radial plates may be perforated 120 or not, as desired.

The screening plates may consist of perforated sheet metal, wire netting or any other suitable material to constitute screening members. It will be seen that by use of 125

the clamping means above described, the screening plates or other screening members can readily be removed and replaced separately or otherwise.

- 5 The shaft 18 may be rotated in any suitable manner. Herein it is rotated by means of a belt-pulley 102 mounted on the free end of the shaft 18 and driven by a belt from any suitable source of power. As the shaft 10
 10 18 rotates, the screening drum rotates with it in the direction of the arrow, Fig. 3. The material fed through the trough 14 falls from the lateral opening 15 into the pockets formed in the drum by the radial plates 40 15 and in this operation may contribute to the rotation of the drum. The material thus arriving in the drum is carried upwardly by the pockets, in which operation the good stock escapes through the interstices or 20 perforations in the screening plates or nettings into a receptacle 104, Figs. 2 and 3, said receptacle having a lateral opening 106, through which the good stock flows out of the machine. The material, consisting of 25 knots, slivers, chives, etc., which is retained in the screening drum by the screening members, is discharged from the buckets as they successively pass through the upper section of their circular path of movement in the 30 rotation of the drum, and is caught in a conveyer by which it is conveyed into the drying drum 108. While said conveyer may be of any suitable construction, it is herein illustrated in the form of a fixed chute 110 35 extending throughout the length of the screening drum and preferably V-shaped, its bottom being inclined downwardly through the central openings 32 of the spider 30 of the screening drum into the forward end of the drying drum, to cause 40 the material in said chute to flow freely into the drying drum. As shown in Figs. 3 and 9, the lateral walls of said chute extend substantially to the inner edges of the radial plate supporting frames 45, one of said walls, namely the one to the right of shaft 18, Fig. 3, preferably extending upwardly 45 considerably higher than the opposite one, so as to catch as much of the material as possible as the latter falls out of the buckets formed by said radial plates.

While it is not essential that, as the screening drum rotates, its lower portion should be submerged in the liquid contained in the receptacle 104 it is preferable that it should do so as thereby the solid material contained in the buckets of the screening drum is kept more or less in suspension which, together with the movement of the cylinder through 55 the liquid and consequent circulation of the liquid through the perforations or interstices of the screening plates or nettings, prevents the solid matter from clinging to said plates to form filters or beds to clog 60 said perforations or interstices.

The end casting 2 of the machine may be provided with a tubular opening 112 extending through the central opening 62 in the spacing member or plate 60 of the screening drum, above the shaft 18, thereby 70 enabling the interior of the drum to be readily inspected from without whenever desired.

Projecting from the outer face of the spider 30, Fig. 2, is a polygonal flange 114, 75 and secured in any suitable manner to the arms 116 of a spider 115, having its hub 117 secured upon the shaft 18, is an inwardly projecting polygonal flange 118, provided at the apices of each one of its angles with 80 a screw-threaded boss 120, one of said bosses 120 being situated in the same plane with each one of the bosses 48 on the spider 30, Fig. 2. A plurality of ribs 122, Figs. 2, 7 85 and 8, extend from the flange 114 on the spider 30 to the flange 118, each rib being provided at its opposite ends with ears 124, 126 by which it is secured to the bosses 120 and 48, respectively, by bolts 128 and 28. The ribs 122 are in the form of T-irons, 90 Fig. 8, the lateral flanges 130 and 132 having their upper surfaces preferably inclined downwardly, as shown in said figure, and the vertical flange 134 being provided with a plurality of holes 136. Peripheral screening plates 138, which may be similar to the screening plates 38 of the screening drum, are laid with their longitudinal edges resting, one on the flange 132 of a rib 122, and the other longitudinal edge resting on the 95 flange 130 of the next following rib 122, the end edges of the screening plates 138 resting on the surfaces of the polygonal collars 114 and 118 of the spiders 30 and 115, respectively. Clamping means, comprising bolts 100 140 extending through the holes 136 of the flange 134 of the ribs 122, clamping members 142 and nuts 144, all of which may in 105 all respects be similar in construction and operation to bolts 80, nuts 81 and the 110 clamping or securing members 82 above described for securing the peripheral screening plates 38 of the screening drum above described in place, may be used removably to 115 secure the peripheral screening plates of the 120 drying drum to the ribs 122. Bolts 140 are 125 herein shown as curved, but may be straight if desired. Preferably, the collar 118 will be greater in diameter than the collar 114, to produce the necessary inclination of the 130 peripheral wall of the drying drum to cause the material therein to pass through and out of said drum.

The arms 116 of the spider 115 are connected by sector-shaped webs 146, which end 125 at a sufficient distance from the outer end of said arms to leave enough space for the escape of the knots. The knots thus pass out of the machine between the arms 116, through the opening left between the part 130

148 of the collar 118 and the edge of the sector 146, as indicated in Fig. 2 by the arrow, as the drum 108 is rotated by the shaft 18.

A shower pipe 150 may be provided, said 5 shower pipe extending longitudinally of the machine and being sustained in suitable bearings 152, 152 provided in the end castings 2 and 3 of the machine, Fig. 2. This pipe 150 extends throughout the length of 10 the two drums 16 and 108 and being located above them, said drums and their contents are showered by the water which escapes from a plurality of openings provided throughout the length of the pipe, thus facilitating 15 the screening operation. A second shower pipe 154, herein located at one side of the drying drum 108 and extending only the length of the latter, may be provided if desired.

20 Instead of using clamping means for the screening plates of the drying drum, similar to those used in the case of the screening drum, a modified form of clamping means shown in Fig. 14 may be used. In this modified form the clamping bolt 156 is shown as provided with a rectangularly bent head 158, and one of the clamping members 160 is shown as provided with a recess to receive said head.

25 It is not deemed necessary to give any further explanation of the mode of operation of the specific apparatus illustrated and described, as such operation will be perfectly clear to those skilled in the art from the description above given of the apparatus itself.

30 It will be apparent that it is not indispensable that all of the features of the invention be used conjointly, since they may be used to advantage separately in various 40 combinations and sub-combinations. It will also be understood that while the invention has herein been described as embodied in the details illustrated, it is not to be considered as circumscribed or limited to these details, 45 or any of them, but it may be variously modified within the true scope of the invention which is definitely set forth by the claims.

Claims:

50 1. In a screening machine, in combination, a screening drum having screening members; and means disposed exteriorly of said drum removably to secure said screening members together and to said screening drum.

55 2. In a screening machine, in combination, a screening drum including screening members; and clamping devices removably to secure said screening members to said drum each clamp device being common to a plurality of screening members.

60 3. In a screening machine, in combination, a screening drum including screening members; screening member sustaining means upon said drum; and devices removably to clamp 65 said screening members upon said

screening member sustaining means each clamp device being common to a plurality of screening members.

4. In a screening machine, in combination, a screening drum including screening members; screening member sustaining means upon said drum; and devices removably to clamp said screening members along their edges upon said sustaining means each clamp device being common to a plurality of screening members.

5. In a screening machine, in combination, a screening drum provided with screening members; frames extending longitudinally of said drum and from the latter's outer periphery radially inward; means provided upon said drum and upon said radial frames to sustain said screening members; and means removably to clamp said screening members upon said sustaining means.

6. In a screening machine, a screening drum comprising supports extending longitudinally of said drum; peripheral screening members carried by said supports and extending from one to another; and devices 90 removably to secure said screening members to said supports each clamp device being common to a plurality of screening members.

7. In a screening machine, a screening drum comprising radial frames extending 95 longitudinally of said drum; radial screening members; means removably to secure said radial screening members to said frames, peripheral screening members; and means removably to secure said peripheral 100 screening members to said frames.

8. In a screening machine, a screening drum and drum carrying means, said drum comprising screen supporting members extending longitudinally of said drum, peripheral screening members, means removably to secure said screening members to said longitudinal supporting members; and devices removably to secure said screening members to said drum carrying means each 110 clamp device being common to a plurality of screening members.

9. In a screening machine, a rotary screening drum and drum carrying means, said drum comprising screen supporting members 115 extending longitudinally thereof, peripheral screening members, means removably to secure said screening members to said longitudinal supporting members and devices removably to secure said screening 120 members to said drum carrying means; each clamp device being common to a plurality of screening members and a shaft about which said drum carrying means is rotatable.

10. In a screening machine, a screening 125 drum and drum carrying means, said drum comprising screen supporting members extending longitudinally of said drum, peripheral screening members, means removably to secure said peripheral screening 130

members to said longitudinal supporting members, end plates, and means removably to secure said peripheral screening members and said end plates to said drum carrying means.

11. In a screening machine, a screening drum and drum carrying means, said drum comprising radial screen supporting frames extending longitudinally of said drum, peripheral screening members, means removably to secure said peripheral screening members to said supporting frames, end plates, means removably to secure said peripheral screening members and end plates to said drum carrying means, radial screening members, and means to secure said radial screening members to said radial frames.

12. In a screening machine, a screening drum and drum carrying means, said drum comprising screen supporting members extending longitudinally of said drum, peripheral screening members, means removably to secure said peripheral screening members to said longitudinal supporting members, end plates at one end of the drum and means removably to secure said peripheral screening members and said end plates to said drum carrying means, a spacing member at the other end of said drum, end plates, and means to secure said end plates to said spacing member.

13. In a screening machine, a screening drum and drum carrying means, said drum comprising screen supporting members extending longitudinally of said drum, peripheral screening members, means removably to secure said peripheral screening members to said longitudinal supporting members, end plates at one end of the drum and means removably to secure said peripheral screening members and said end plates to said drum carrying means, a spacing member at the other end of said drum, end plates, and means removably to secure said peripheral screening members and end plates to said spacing member.

14. In a screening machine, a screening drum and drum carrying means, said drum comprising radial screen supporting frames extending longitudinally of said drum, peripheral screening members, means removably to secure said peripheral screening members to said supporting frames, end plate at one end of the drum, means removably to secure said peripheral screening members and end plates to said drum carrying means, a spacing member at the other end of the drum, end plates for the latter,

means removably to secure said peripheral screening members and end plates to said spacing member, radial screening members, and means to secure said radial screening members to said radial frames.

15. In a screening machine, in combination, a screening drum; a drying drum; the single supporting means for said drums being common thereto; and a shaft about which said common supporting means is rotatable.

16. In a screening machine, in combination, a screening drum, a drying drum, a supporting means common to both said drums and suspending them on either side thereof and a shaft about which said common supporting means is rotatable.

17. In a screening machine, in combination, a screening drum; a shaft about which said screening drum is rotatable; and an inspection opening for the interior of said drum from the exterior of the machine.

18. In a screening machine, in combination, a screening drum; a shaft about which said screening drum is rotatable; radial members constituting pockets in said drum; and a trough or conveyer for conveying material from said drum, one of the walls of said trough being higher than the other.

19. In a screening machine, in combination, a screening drum, a shaft about which said screening drum is rotatable, radial members constituting pockets in said drum and a trough or conveyer extending into said drum for conveying the material from said drum, one of the walls of said trough being higher than the other.

20. In a screening machine, in combination, a screening drum, a shaft about which said screening drum is rotatable, radial members constituting pockets in said drum and a trough or conveyer extending into said drum and substantially throughout the length thereof for conveying the material from said drum, one of the walls of said trough being higher than the other.

21. A screening drum having longitudinal ribs, said ribs having outwardly extending portions, screening members engaging said ribs and means carried by said outwardly extending portions to clamp them thereto.

In testimony whereof, I have signed my name to this specification, in the presence of two subscribing witnesses.

ANTON J. HAUG.
